APPARATUS FOR STUDYING
ILLUMINATION

Ellis Humphreys, St. Louis, Mo., assignor to
Mississippi Glass Company, St. Louis, Mo., a
corporation of New York

Application November 13, 1942, Serial No. 465,432

7 Claims. (Cl. 35—19)

An object of this invention is to provide apparatus for testing and/or demonstrating illumination under a variety of conditions.

More particularly, the invention provides means for readily trying out various details of construction of a contemplated building in order to determine the most desirable arrangements for daylight illumination.

Further and other objects and advantages will be apparent from the specification and claims, and from the accompanying drawings which illustrate what are now considered to be the preferred embodiments of the invention.

In the drawings:

Figure 1 is an isometric view of the device;
Fig. 2 is a schematic cross-section of one of the illuminating units; and

Fig. 3 is a view similar to Fig. 1, but illustrating a modification.

In the drawings 10 is a model of a building which may have a removable roof 12 with an observation opening 14 on the rear thereof. This roof may be replaced by another, representing any desired type, such as monitor, saw-tooth, flat roof with curb skylights, etc., each having an observation opening 14.

The front sides of the roofs and the front walls of the building are provided with openings 16. In the roof these openings represent skylights or the like and in the side walls they represent ordinary wall sash or any other type of suitable window opening. Each opening 16 is provided with a guide 18 on each side thereof and a bottom stop 20 for holding pieces of glass or other material cut to proper size and shape. Division bars in the form of wire rods 22 may be placed in openings 16 if desired.

In order to simulate sunlight, sources of parallel light rays are provided as shown, for instance, in Fig. 2, in which 24 is an electric bulb preferably having a small filament, from which the light passes through lenses such as 26, 28 to emerge as parallel rays 30. Each unit is enclosed in a box or tube 32 closed at the end behind the lamp. A reflector 34 may be placed behind the lamp if desired. The wiring is conventional and therefore is not illustrated.

In model 10, as illustrated, there are three openings 16 in the side wall, and a roof opening directly above each wall opening. There are three light units 32 mounted in a housing 36, 38 and spaced apart horizontally to correspond with the spacing of openings 16, each unit being aligned with one of the openings.

Housing 36, 38 is pivotally supported by trun-

nions 40 in arms 42 which are mounted to swing upwardly in an arc about studs 44. A coil spring 46 around each trunnion holds the housing impotively, by friction, in any position to which it may be manually adjusted relatively to arms 42.

Arms 42 may be held in any adjusted position by links 48 pivotally connected at 50 to arms 42, the other ends of links 48 being guided horizontally by tracks 52 in the ends of base 54 on which the apparatus is mounted. A thumb screw 56 serves to lock in any adjusted position, links 48, arms 42 and the lamp housing.

In operation, base 54 is placed on a horizontal table or bench. Pointer 58 pivotally supported at 60 and held vertical by its pendulous weight 62 will indicate on scale 64, the angle of the rays from the horizontal.

In use, the light source is illuminated and elevated and tipped to the desired elevation and angle. As shown in the illustration, the position of the light source, substantially horizontal, would, for the purpose of the device, duplicate the light received from the sun on the side wall 25 of a building facing west at sundown. Similarly, by elevating and tipping the light source, other sunlight conditions can be simulated, both in respect to the side-wall openings and the openings in whichever type of roof may be in place.

Through the observation opening in the roof, or through the top of the building itself if no roof be in place and the side-wall openings are being considered, the effects of different types of glass in the window openings may be observed.

For instance, if the side-wall openings are being considered, and if no glass is interposed, or if clear glass is used in the guides, it will be seen that bright spots of light, crossed by the dark shadows of the bars 22, are projected upon the floor, or rear wall, or both, in the interior of the building. It is graphically recognizable that this bright and dark illumination is not good for most types of industrial working. A pencil may be held inside the building representing a building column, and the effect of the shadow it casts may be noted. By inserting different types of configurated glasses in the windows, it can be demonstrated how the light can be diffused, shadows eliminated and bright spots removed.

By inserting a piece of opaque material in one of the openings, it can be demonstrated how the interior of the building can still be adequately illuminated by the use of ribbed or prism glass in the remaining openings. It can thus be shown that good daylight illumination can be obtained

where it is not possible to have substantially the entire side of a building provided with openings for the admission of daylight.

In the same way, the effect of different types of openings for the admission of daylight through the different types of roofs in conjunction with the various glasses designed for this purpose may be studied and demonstrated under many different conditions.

In Fig. 3, there is illustrated a modification which is sometimes preferable to the apparatus shown in Figs. 1 and 2. Referring to Fig. 3, the model 11 of the building is similar to that shown in Fig. 1, except that it is shown provided with two front windows and two skylights and is secured to a turn table 13 rotatably mounted in the central portion of the circular base 15 about the vertical axis of the latter. The base 15 is peripherally calibrated or provided with indicia representing the points of the compass. On the east-west diameter of the base 15, a semi-circular bail 17, having a radius slightly larger than that of the base 15, is pivotally connected at its opposite ends to the edge or periphery of the base. The lamp housing 19, containing two illuminating devices such as those shown at 32 in Figs. 1 and 2, is mounted for sliding movement along the bail 17 so as to direct its parallel rays radially of the bail and toward the model 11. This slidable connection is effected by means of a clip or bracket 21 secured to the rear of the lamp housing 19 and frictionally gripping the opposite edges of the bail 17 so as impositively to lock the housing 19 in any position of adjustment along the bail. The bail 17 is calibrated, or provided with time-representing indicia, as shown, to facilitate adjustment of the light source 19 in accordance with positions of the sun during the daytime. In order to adjust the bail 17 and its sun-simulating housing 19 for different latitudes (on one side of the equator) a quadrant-shaped arcuate strip 23 having a radius slightly larger than that of the base 15 is pivotally connected to the edge of the base 15 at the "south" position of the latter. The bail 17 has a bracket or clamp 25 secured thereto through which the strip 23 slides and a manually operable set screw 27 is provided in the bracket for clamping the bail 17 to the strip 23 in any one of the selected positions along the strip 23. The quadrant-shaped strip 23 is calibrated, or provided with indicia showing latitude from "0°" at its free end to "90°" at, or adjacent to its pivotal connection to the base 15. It will be noted that the clip 21 and the bracket 25 are so constructed that the clip may be slid past the bracket.

When the apparatus is not in use, the bail 17 may be disengaged from the strip 23, the housing 19 slid to the uppermost position on the bail, and the bail and housing may then be swung rearwardly and downwardly until the housing rests upon the base 15. The disengaged strip 23 may then be swung about its pivot to a position in which it lies wholly along the edge of the base 15. The extra roofs may then be laid on the base on the side of the model 11 opposite the housing 19. Thus, when not in use, the structure is compact and storage, carrying and shipment facilitated. The folded apparatus may be readily and conveniently carried in a cylindrical carrying case (not shown) having an inside diameter slightly greater than the base 15 and an inside height slightly greater than the height of the model 11 plus the thickness of the base.

In use, the model 11 may be given any desired

exposure by virtue of its being mounted on the turntable 13. The turntable is impositively held by friction in any selected position. The light-source 19 is adjustable together with the bail 17 about the pivotal axis of the latter by unscrewing the set-screw 27, sliding the clamp along the strip 23 to the desired position (selected according to the latitude of the particular place of use), and then held in that position by tightening the screw 27. The light source 19 may also be readily shifted along the bail 17 (representing the apparent path of the sun on some particular day of the year in accordance with the sun's position at different times during the day. While the apparatus shown in Fig. 3 is not absolutely accurate except for a certain location at a certain time each year, it is sufficiently accurate and satisfactorily operative for its intended purposes and uses.

Figs. 1 and 2, and the description thereof herein, are the same as in my application Serial No. 432,754, filed February 28, 1942, in the United States Patent Office, entitled "Device for studying illumination," and of which the present application is a continuation in part.

It is understood that the invention is not limited to the specific embodiment herein illustrated and described, but may be used in other ways without departure from its spirit as defined by the following claims.

What I claim is:

1. Apparatus for studying the daylight illumination of the interior of a proposed building through its windows, comprising means for supporting a model of the building with openings for said windows, in combination with means for directing parallel rays of light through said openings into said model, said model having an observation opening in the rear thereof.

2. The invention set forth in claim 1 in which said openings are provided with means for supporting therein various kinds of glass or the like, for the purpose set forth.

3. Apparatus for studying the daylight illumination of the interior of a proposed building through its windows, comprising means for supporting a model of the building with openings for said windows, in combination with means for supporting an illuminating device adapted for directing parallel rays of light into said model through said window openings, said device being adjustable in position for simulating sunlight conditions for any daylight hour.

4. Apparatus for studying the daylight illumination of the interior of a proposed building through its windows and comprising, in combination, a model of the building with openings for said windows, and means for supporting an illuminating device adapted for directing parallel rays of light into said model through said window openings, said device being adjustable in position for simulating sunlight conditions for any daylight hour, said supporting means including a bail representing an apparent path of the sun.

5. Apparatus for studying the daylight illumination of the interior of a proposed building through its windows and comprising, in combination, a model of the building with openings for said windows, and means for supporting an illuminating device adapted for directing parallel rays of light into said model through said window openings, said device being adjustable in position for simulating sunlight conditions for any daylight hour, said supporting means including a

pivottally mounted bail representing an apparent path of the sun and adjustable about its pivotal axis in accordance with latitude.

6. The invention set forth in claim 1 in which supporting means, including a bail representing an apparent path of the sun, are provided for supporting the source of light.

7. Apparatus for studying the daylight illumination of the interior of a proposed building through its windows and comprising, in combi-

nation, a model of the building with openings for said windows, a base upon which said model may be turned about a vertical axis for different exposures, a bail representing an apparent path of the sun pivotally connected to said base, a sun-simulating source of light slidably mounted on said bail, and means whereby said bail may be held in various positions of adjustment about its pivotal axis in accordance with latitude.
